A. M. MERTZANOFF

CONTROL DOOR FOR HEATING APPARATUS

Filed April 30, 1923

Patented Aug. 17, 1926.

1,596,442

UNITED STATES PATENT OFFICE.

ANDRÉ M. MERTZANOFF, OF NEW YORK, N. Y., ASSIGNOR TO AMERICAN RADIATOR COMPANY, OF NEW YORK, N. Y., A CORPORATION OF NEW JERSEY.

CONTROL DOOR FOR HEATING APPARATUS.

Application filed April 30, 1923. Serial No. 635,533.

My invention relates to improvements in heating apparatus, and the same has reference more particularly to that type of heating apparatus in which the operation thereof may be automatically controlled.

Further, said invention has for its object to provide a heating apparatus in which the fuel consumption and the operation of the apparatus are positively controllable by thermosensitive means which is automatically responsive to the conditions obtaining within the apparatus.

Further, said invention has for its object to provide a heating apparatus of the type specified by means of which the automatic control of the draft, and the rate of fuel consumption cannot be impaired or interfered with by the manipulation of the doors or closures for sealing the fuel opening, slicing opening or ash pit opening.

Further, said invention has for its object to provide a heating apparatus of the type specified having a cold air inlet and means for automatically controlling the supply of air thereto, and having the usual fuel supply opening and ash pit opening provided with doors, and one of said doors being so constructed and arranged with respect to the other thereof as to render it impossible to open one of said doors without first opening the other thereof.

Further, said invention has for its object to provide a heating apparatus of the type specified having the usual fuel supply opening and ash-pit opening, and a door primarily controlling the fuel supply opening but so constructed and arranged with respect to the ash-pit opening that the latter cannot be opened or uncovered without first opening and maintaining open the door of the fuel supply opening, and also rendering it impossible to close said fuel supply door without closing or sealing the ash-pit opening.

Further, said invention has for its object to provide a heating apparatus of the type specified equipped with automatic means for supplying cold air to the ash-pit, and means which render impossible any interfering with the operation of automatic controlling means by the manipulation or adjustment of the doors of the fuel supply opening and of the ash-pit opening, or either thereof.

Further, said invention has for its object to provide a heating apparatus having means for preventing the overheating thereof, and

the resulting cracking or burning out of said apparatus or any of the parts thereof.

In the operation of boilers equipped with automatic or thermosensitive draft controlling means, it has been found that the operator, particularly where the boiler is of the smaller sizes used for residence heating, frequently seeks to accelerate the operation of the boiler, and to that end attempts further to regulate the same by manipulating the doors of the ash-pit and the fuel supply openings, or either thereof, and as a result the normal operation of the automatic draft controlling device is either materially impaired, or the device rendered wholly inoperative, and the proper and intended operation of the boiler rendered impossible. To provide means for preventing such improper manipulation of the furnace doors, and to insure the proper operation of the thermosensitive or automatic draft controlling device is, therefore, the principal object of the present invention.

Other objects will in part be obvious, and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings illustrating one form or embodiment of my said invention—

Figure 1 is a front elevation showing a boiler with my invention embodied therein;

Fig. 2 is a similar view with the controlling door opened, and

Fig. 3 is a central longitudinal section.

In said drawings 10 designates a boiler, which for the purpose of illustrating the invention, is here shown composed of a front section 11, a back section 12, and a plurality of intermediate sections 13. The front section is provided with the usual fuel supply opening 14, slicing opening 15 having a separate hinged door 15^a, and an ash-pit opening 16 also having a separate hinged door 16^a. The back section is provided with a smoke outlet 17, and a cold air inlet 18 communicating with the interior of the boiler below the grate 19. The cold air inlet 18 is provided with a cover 20 which is hinged along its upper edge, and its lower free edge is connected to a rod 21 whose upper end is

pivottally connected to one end of a lever 22 of a thermosensitive device 23 mounted upon the top of the boiler adjacent the rear end thereof.

5 The back section 12 and a number of the intermediate sections 13 are provided adjacent to their upper portions with registering transverse, hollow water members 24 forming a horizontal flue 25 extending from the front of the combustion chamber 26 to the smoke outlet 17.

Upon the front of the front section 11 is secured a rectangular plate or casting 27 having openings, registering respectively 15 with the fuel supply opening 14, slicing opening 15, and ash-pit opening 16 in the front section of the boiler, and adjacent to one of the vertical edges of said plate 27 are provided hinge members 31, 31 upon which 20 work the registering hinge members 32, 32 of a door 33 having a rearwardly extending rim or flange 34. The door 33 is provided with a transverse rib or web 35 in order to form a complete peripheral enclosure or 25 door proper for the fuel supply opening 14. The lower portion of the door 33 extending below the rib or web 35 forms an extension or apron and is of such size that the same 30 completely encloses or controls the slicing opening 15 and ash-pit opening 16, and the individual doors therefor.

The outer surface of the plate 27, and the rim or flange 34, as well as the transverse rib or web 35 are preferably ground in order 35 to form a substantially air tight closure, since all the air necessary to support combustion is admitted by way of the cold air inlet 18 at the rear of the boiler, and controlled by the thermosensitive device 23 and 40 connected parts.

The operation of the boiler will be largely 45 obvious. The fuel is introduced through the fuel supply opening 14, and the ashes withdrawn through the opening 16 in the usual manner. The supply of air is provided wholly by way of the inlet 18, and the products of combustion and the hot gases pass from the combustion chamber 26 through the flue 25 to the smoke outlet 17 to the stack.

50 The supply of cold air through the inlet 18 at the rear of the boiler is automatically controlled by the thermosensitive device 23 acting upon the cover 20, and serves to open or close the same in accordance with the conditions obtaining within the boiler.

By reason of the construction of the fuel supply door 33, the automatic actuation of the cover 20 of the cold air inlet 18 becomes positive and certain, and any attempt 60 to force the boiler beyond the predetermined degree, as determined by the thermosensitive device is rendered impossible. The only way in which the fire can ordinarily be forced in the usual type of boiler or heating apparatus is by opening the draft in the smoke

outlet and opening the ash-pit door. This, however, is rendered impossible in the present instance since in order to open and maintain open the ash-pit door 16^a, the fuel supply door 33 must also be opened, and 70 when this is done air will simultaneously be admitted to the boiler above and below the grate through the fuel opening 14 and ash-pit opening 16, and, as the fuel opening 14 offers the path of least resistance 75 to the passage of cold air, the greater part or volume of the air entering the boiler will pass through the fuel opening 14, and consequently check all tendency to force the fire. It also follows that the closing of the door 33 controlling the fuel opening 14 will act 80 to close the ash-pit door 16^a, as well as the slicing door 15^a, should that have been opened, and reestablish the normal operating conditions within the boiler, and the 85 taking of the entire air supply through the air inlet 18 at the back of the boiler.

It is to be noted that in order to insure the absolutely automatic operation of the draft control, the door controlling the fuel supply opening 14 must be so constructed and arranged with reference to the ash-pit opening 16, that the latter cannot permit cold air to enter therethrough, or permit the door thereof, (when said opening is provided with one), to be opened without opening the former, and that the former cannot be closed without discontinuing the supply of cold air to the ash-pit opening, or closing the door thereof. When the boiler is 100 provided with a slicing opening 15, or any other openings in addition to the fuel and ash-pit openings, the fuel supply door must, of course, similarly control such other or additional opening or the doors thereof in 105 order to prevent, or in any way affect the due operation of the automatic draft controlling means.

It is to be noted that while I have shown and described my said invention in connection with a hot water boiler the same is 110 equally applicable to steam boilers, hot air furnaces, stoves, and other forms of heating apparatus, and while the same is of particular advantage in connection with heating 115 apparatus wherein the draft is controlled by automatically operated regulating devices, the same is nevertheless of value when applied to heating apparatus not so equipped.

Having thus described my said invention what I claim and desire to secure by Letters Patent is:

1. A heating apparatus having a fuel supply opening, an ash-pit opening, and means 120 for controlling said openings and serving, when in closed position, to prevent the admission of air therethrough; the portions of said means controlling said fuel supply opening and said ash-pit opening coacting 125

to prevent the admission of air through said ash-pit opening without simultaneously admitting air through said fuel supply opening, substantially as specified.

5 2. A heating apparatus having a fuel supply opening, an ash-pit opening, means for controlling said openings and serving, when in closed position, to prevent the admission of air therethrough; the portions 10 of said means controlling said fuel supply opening and said ash-pit opening coacting to prevent the admission of air through said ash-pit opening without simultaneously admitting air through said fuel supply opening, and a separate draft inlet for admitting below the fuel the normal supply of air necessary to support combustion, substantially as specified.

15 3. A heating apparatus having a plurality of openings, including a fuel supply opening, means for controlling said openings and serving, when in closed position, to prevent the admission of air therethrough; the portions of said means controlling said 20 openings coacting to prevent the admission of air through certain of said openings without simultaneously admitting air through said fuel supply opening, a separate draft inlet for admitting below the fuel the normal supply of air necessary to support combustion, and means for controlling the admission of air to said draft inlet, substantially as specified.

25 4. A heating apparatus having a plurality of openings, including a fuel supply opening and an ash-pit opening, a separate draft inlet for admitting below the fuel the normal supply of air necessary to support combustion, means for automatically controlling the admission of air to said draft inlet, and means for controlling said first 30 named openings and serving, when in closed position, to prevent the admission of air through said first named openings; said last named means serving to insure the admission of air through certain of said first named openings when air is admitted through other thereof, substantially as specified.

35 5. A heating apparatus having a plurality of openings, including a fuel supply opening, a separate draft inlet for admitting below the grate the normal supply of air necessary to support combustion, means for automatically controlling the admission of air to said draft inlet, and means for controlling said first named openings and serving, when in closed position, to prevent the admission of air through said first 40 named openings; the portions of said means controlling said first named openings coacting to insure the admission of air through said fuel supply opening simultaneously with the admission of air through other of said first named openings, substantially as specified.

6. A heating apparatus having an ash-pit opening, a fuel supply opening, a separate draft inlet for admitting below the fuel the normal supply of air necessary to support combustion, means for automatically controlling the admission of air to said draft inlet, and closures for said fuel supply opening and said ash-pit opening serving, when in closed position, to prevent the admission of air through said fuel supply and ash-pit openings; the closure for said fuel supply opening serving to control the operation of the closure for said ash-pit opening, substantially as specified.

7. A heating apparatus having an ash-pit opening, a fuel supply opening, a separate draft inlet for admitting below the grate the normal supply of air necessary to support combustion, means for controlling the admission of air to said draft inlet, and a member for controlling said fuel supply opening and enclosing said ash-pit opening, and serving, when in closed position, to prevent the admission of air through said fuel supply opening and said ash-pit opening, substantially as specified.

8. A heating apparatus having an ash-pit opening, a fuel supply opening, a separate draft inlet, means for controlling the admission of air to said draft inlet, and means for controlling said first named openings and serving, when in closed position, to prevent the admission of air through said first named openings and rendering said ash-pit opening inoperative to admit air therethrough when said last named means is adjusted to prevent the admission of air through said fuel supply opening, substantially as specified.

9. A heating apparatus having an ash-pit opening, a fuel supply opening, a draft inlet for admitting below the grate the normal supply of air necessary to support combustion, means for controlling the admission of air to said draft inlet, a separate door for said ash-pit opening, serving, when in closed position, to prevent the admission of air through said ash-pit opening, and a door for closing said fuel supply opening and enclosing said ash-pit opening and the door therefor; said door serving, when in closed position, to maintain said ash-pit opening closed whereby to prevent the admission of air through said ash-pit opening without simultaneously admitting air through said fuel supply opening, substantially as specified.

10. A heating apparatus having an ash-pit opening, a fuel supply opening, and a door for closing said fuel supply opening and enclosing said ash-pit opening, and serving, when in closed position, to prevent the admission of air through said openings; said door serving to prevent the closing of said fuel supply opening without clos-

ing said ash-pit opening, whereby to prevent the admission of air to said ash-pit opening without simultaneously admitting the same to said fuel supply opening, substantially as specified.

11. A heating apparatus having an ash-pit opening, a fuel supply opening, a separate draft inlet for admitting below the fuel the normal supply of air necessary to support combustion, means for controlling the admission of air to said draft inlet in response to conditions within said heating apparatus, and a door for said fuel supply opening having an extension enclosing said ash-pit opening, and serving, when in closed position, to prevent the admission of air through said fuel and ash-pit openings; said door serving to prevent the closing of said fuel supply opening without closing said ash-pit opening, whereby to prevent the admission of air through said ash-pit opening without simultaneously admitting air through said fuel supply opening, substantially as specified.

12. A heating apparatus having an ash-pit opening, a fuel supply opening, a separate draft inlet for admitting below the fuel the normal supply of air necessary to support combustion, means for controlling the admission of air to said draft inlet in response to conditions within said heating apparatus, and a door for said fuel supply opening having an extension enclosing said ash-pit opening, and serving, when in closed position, to prevent the admission of air through said fuel and ash-pit openings; said door serving to prevent the admission of air through said ash-pit opening without simultaneously admitting air through said fuel supply opening, substantially as specified.

Signed at the city of New York, in the county and State of New York, this 22d day of March, one thousand nine hundred and twenty-three.

ANDRÉ M. MERTZANOFF.
